UNITED STATES PATENT OFFICE.

CHARLES L. ZIMMERMAN, OF CHICAGO, ILLINOIS.

ACETYLENE-GAS GENERATOR.

SPECIFICATION forming part of Letters Patent No. 634,319, dated October 3, 1899.

Application filed February 25, 1898. Serial No. 671,604. (No model.)

To all whom it may concern:

Be it known that I, CHARLES L. ZIMMERMAN, of Chicago, in the county of Cook and State of Illinois, have invented certain new and useful Improvements in Acetylene-Gas Generators, of which the following is a specification.

This invention relates to acetylene-gas generators, and refers more specifically to an improved portable generator suitable for vehicles or for domestic purposes.

Among the objects of the invention are to provide a generator of the character referred to in which the liquid-reservoir, while arranged in immediate juxtaposition to the generating-chamber, so that the connection therebetween may be most simple in construction, is nevertheless so connected with said generating-chamber as to minimize the transmission of the heat of the latter to the liquid of the reservoir, thereby permitting the liquid to remain cool and the flow of the same to the generating-chamber to remain more constant and uniform; to provide a simple and direct-acting valve to control the port affording communication between the reservoir and generating-chamber, which valve is controllable from the outside of the generator through a device which serves at once as a closure for the filling-aperture of the reservoir and to form a regulating device which controls the position of the valve and co-operates with a graduated scale; to provide an improved follower by means of which the carbid and resin will be held in compact form; to so construct and arrange the carbid-receptacle that it shall be to a great extent insulated from the outer walls of the generator, and to provide a generally-improved, simple, and efficient construction of generator which may be most economically manufactured and will be particularly free from liability to get out of order.

The invention consists in the matters hereinafter described, and more particularly pointed out in the appended claims, and the same will be readily understood, reference being had to the accompanying drawings, in which—

Figure 1 is an axial vertical sectional view taken on a diameter passing axially through the headlight also. Fig. 2 is a fragmentary

horizontal sectional view taken on line 2 2 of Fig. 1. Fig. 3 is a top plan view of the upper end of the reservoir, showing particularly the graduated scale surrounding the valve-controlling closure. Fig. 4 is a detail plan view of the holding-clamp whereby the generator may be attached to a bicycle.

Referring to the drawings, my invention is therein shown as embodied in a bicycle-lamp; but it will be understood that by simply providing a suitable frame or bracket for the support of a chimney or shade the generator is also well adapted for domestic purposes.

In the drawings, A designates the base or body of the generator, which forms the generating-chamber, and B the liquid-reservoir surmounted thereon. The generating-chamber consists in the present instance of a cup-shaped shell a, preferably spun or otherwise suitably formed with its sides and upper end integral, said end being desirably made convex, and a removable lower end cap or closure a', having screw-threaded connection with the port a². The end closure is conveniently struck up or formed so as to provide an annular vertical shoulder a², which is screw-threaded to fit within a correspondingly-threaded ring a³, set in the lower end of the shell a, and a radially-projecting portion or shoulder a⁴, which underlies the lower end of the shell and between which and the latter is interposed a packing-gasket a⁵. Desirably the outer periphery of said closure is formed into a roll a⁶ to provide a suitable finish and to afford a base upon which the lamp may rest firmly. The lower end closure is also desirably made outwardly convex, as indicated clearly in the drawings.

C designates a cup-shaped carbid-receptacle having cylindrical sides c and a convex lower end c', said receptacle being of less depth and of smaller cross-sectional area than the interior of the generating-chamber and the degree of curvature or convexity of the lower end thereof being greater than that of the end of the cap a', so as to provide an insulating-space c², completely surrounding said carbid-receptacle except at the central portion of the lower end thereof, which rests directly upon and is rigidly attached to the said removable bottom of the generator. The carbid-cup is desirably and as herein shown

formed of a single piece of sheet metal struck up or spun into suitable form.

- Within the carbid-cup is arranged to fit and slide a follower D, consisting of a sheet-metal plate or diaphragm having a peripheral flange d turned at right angles to the main plane of the follower and arranged to fit against the side walls of the cup and provided also at its center with a relatively large opening d', which is surrounded by an up-standing integral flange d'', preferably made bell-shaped, as indicated in the drawings. In order to insure a better frictional engagement of the follower with the side walls of the carbid-receptacle, a plurality of parallel cuts d''' are arranged to extend inwardly from the edge of the flange at a short distance from each other, so as to form intervening tongues d'', which are sprung outwardly slightly in the formation of the follower, so as to act as spring-tongues which bear against the interior of the cup, and thus insure a uniform frictional engagement with the latter throughout the movement of the follower.
- The reservoir B is formed with downwardly converging lower sides and is directly connected with the central part of the upper end of the generator, the construction being such that the point of connection between said parts is of relatively small area. The reservoir is in the present instance and desirably made spherical of a single piece of sheet metal spun or otherwise brought to the required form. Through the meeting portions of the walls of the reservoir and generating-chamber are formed registering apertures b' a'', respectively, within which is seated a cylindrical valve-body E, the main part of which depends within the generating-chamber. e designates a tapering needle-valve port formed axially through said valve-body, the upper end thereof, e', being enlarged, so as to act as a guide to facilitate the entrance of the valve therein.
- E' designates a needle-valve adapted to fit the port of the valve-body and provided with a stem e'', which extends axially up through the liquid-reservoir and is connected with a relatively large screw cap or closure F, set in the top of said reservoir. Desirably the screw-threaded seat within which the closure F fits is formed by means of a collar b'', permanently soldered or otherwise secured in the shell of the reservoir, the upper or exterior end b''' of said collar being made flat to form a gasket-seat, between which and the under side of closure F is interposed a packing or gasket f. This gasket or packing is preferably made of soft rubber or other compressible material, so as to act as a friction ring or spring which will serve to hold the closure in adjusted position even though the latter be unscrewed to a considerable extent to adjust the needle-valve some distance away from its seat.

Around the periphery of the closure F upon the outer wall of the reservoir is formed a se-

ries of graduating-marks forming a scale f', (see Fig. 3,) with which is adapted to coöperate an indicator or downwardly-extending pointer f'', carried by the closure F. A screw-stud f''' is inserted in the wall of the reservoir in the path of the pointer f'', so as to prevent the closure from being turned more than a complete revolution unless it be desired to withdraw the latter entirely, together with the connected needle-valve, in which case the screw-stud must first be removed.

The closure F is provided with a relatively large aperture f'', extending centrally therethrough, forming a filling-aperture through which the liquid may be charged into the reservoir, which aperture is internally screw-threaded to receive a screw-plug F'. In order that there may be no excess of pressure in the reservoir, so as to interfere with the uniform feed of the liquid through the valve-port, the screw-plug F' is provided with one or more vent-apertures f'''.

In order that the liquid may be directed from the port of the valve to the central part of the body of carbid contained within the cup regardless of the jolting and tilting of the generator, a guide-finger G is connected with the lower end of the valve-body and arranged to extend downwardly from the latter through the central aperture of the follower and into the body of carbid, the construction and arrangement of this guide being such that the liquid issuing from the port will flow down the guide instead of dropping freely. In order that the liquid may flow steadily down the guide rather than in the form of successive drops, the needle-valve is made long enough to project through and below the valve-body, the guide G being brought so close to its path that the liquid will readily bridge the space between said parts, and hence maintain a continuous stream.

In order to prevent an excess of pressure in the generator-chamber, a safety-valve is desirably provided in the upper part thereof, this valve being of any well-known or suitable construction.

H designates a bracket soldered or otherwise rigidly secured to the side wall of the generator-chamber conveniently about midway of the height thereof, said bracket being desirably made in the form of a casting, so as to afford a rigid support for the headlight I, which is mounted thereon. In the upper side of the bracket is formed an interiorly-screw-threaded burner-nozzle socket h, within which is seated a burner-nozzle H'. The socket h is preferably of relatively large diameter and is somewhat deeper than required to connect the burner-nozzle, so as to form a small gas-chamber h' below the end of the nozzle. From this chamber a relatively small gas-passage h'' leads back through the bracket and communicates with a small short pipe h'', which extends through the wall of the generating-chamber and is turned downwardly at its inner end, so as to stand slightly away

from the inner wall of the chamber and open downwardly, this arrangement being adopted to prevent ingress of any moisture which may condense and trickle down the sides of the generator-chamber or be splashed up from below. The provision of the gas-chamber h' is a feature of importance, inasmuch as it aids greatly in preventing the burner from being extinguished by jars or jolts by supplying a column of gas adjacent to the inlet of the burner-nozzle, which prevents the stream or column of gas from being easily interrupted to an extent sufficient to extinguish the flame.

h^3 designates a socket bored to extend from the upper surface of the bracket, near the outer end thereof, obliquely downwardly and inwardly entirely through the bracket. This socket is adapted to receive the shank h^4 of a support H^2 , which is provided at its upper end with a pair of oppositely-projecting curved arms h^5 (see Fig. 2) and a third forwardly-projecting arm h^6 , which severally embrace the lower side of the headlight I and support the latter in position. Said arms h^5 are suitably secured to the headlight, preferably by riveting, as indicated at h^7 . In order to prevent rotative movement of said headlight-support relatively to the bracket, it is provided at the upper end of its shank h^4 with a head having a lip or lug h^8 , which fits against the flat front side h^9 of the bracket. The lower end of the shank, which projects through and beyond the bracket, is screw-threaded and provided with a suitable thumb-nut h^{10} .

The headlight I is of novel construction and comprises a bell-shaped shell i , preferably spun or otherwise formed from a single piece and within the front end of which is mounted a double convex lens K. The rear end body portion i' , forming an extension of the bell-shaped part i , is made approximately cylindric, and the end thereof is closed by a slightly-convex end wall i^2 . Within the bell-shaped part is arranged a removable polished frusto-conical reflector i^3 , which is sufficiently smaller than the interior of the shell to permit a surrounding insulating-space i^0 , and at the rear of the combustion-chamber is mounted a concave reflector i^4 , which is detachably secured to the end of the wall of the headlight. The cylindric portion of the end of the wall of the headlight-body is desirably made perforated and is also provided with the usual colored lenses i^5 . At its lower side the headlight is provided with an opening i^6 , adapted to receive the upper end of the burner-nozzle, which latter is provided with an umbrella-shaped head h^{11} , which substantially occupies the opening i^6 and is provided with a plurality of air-inlet apertures h^{12} , which permit the access of an ample supply of air to the burner-jet.

At its upper side, vertically above the burner-nozzle, the headlight is provided with a hood I, provided with a slightly-enlarged and somewhat-convex closed upper end and de-

sirably made of perforated metal or foraminated both at its sides and top. Through the central part of the closed upper end of the hood is formed a lighting-aperture i^7 , and beneath this aperture is arranged a baffle-plate i^8 , provided with a central aperture i^9 , which registers with the aperture i^7 . The baffle-plate is supported free from and some distance below the upper end of the hood conveniently by means of rivet-studs i^{10} .

J designates as a whole a novel and extremely simple and effective form of supporting-clamp, by means of which the lamp may be conveniently attached to a bicycle steering-head or the like. Said clamp comprises a T-shaped bracket desirably formed of strap metal and soldered or otherwise secured to the rear side of the lower part of the lamp, so as to project at right angles therefrom. The end of said bracket is provided with a thumb-screw aperture j' , concentrically with which is rigidly secured a serrated friction-plate j^2 .

j^3 designates a ring-shaped clasp adapted to fit upon the part to which the lamp is to be attached, said clasp being also made of strap metal and provided with a pair of radially-projecting ears $j^4 j^5$, through which is inserted a clamping-screw j^6 .

j^7 designates an arm formed integrally with the ear j^5 of the clasp and arranged to extend at right angles thereto, as indicated clearly in the plan view, Fig. 4. Said arm is provided with a clamping-screw aperture adapted to register with that of the bracket J and is also provided on its proximate face with a rigidly-attached coöperating friction ring or disk j^8 . Through the bracket J and arm j^7 of the clasp is inserted a suitable clamping-screw j^9 , provided with a thumb-nut j^{10} . Obviously by means of this construction the lamp may be rigidly secured at any desired angle and brought very close to the point of support when the clasp and bracket are clamped in the position indicated in the drawings, or the clasp may be turned so as to form an extension of the bracket J, as found desirable or as may be necessary to avoid interference with parts of the vehicle upon which it is mounted.

The operation of the lamp will doubtless be obvious from the foregoing description, but may be briefly described as follows: The lower end cap of the generator having been removed, together with the carbid-cup, the latter will be partly filled with carbid, either in pulverulent or caked form, the follower pressed closely down into contact with the same, and the parts returned to place. The needle-valve being in closed position, the screw-plug in the reservoir is next removed and a suitable charge of liquid poured in through the filling-aperture. The lamp is now in readiness for operation and may be started by simply turning the closure F so as to open the valve slightly, whereupon the liquid will begin to trickle down upon the car-

bid and generate gas. The gas generated passes out through the pipe h^2 to the nozzle, which may now be ignited by simply holding a lighted match adjacent to the ignition-aper-
ture i^1 . Should the rate of generation be-
come too great, the gas will escape through the safety-valve or through the body of the liquid contained in the reservoir and thence through the vent f^5 . Whenever it is noticed
10 that gas is being generated faster than it is consumed by the burner, the needle-valve may be instantly adjusted so as to reduce the supply of liquid, and thereby reduce the quantity of gas generated.
15 It is to be noted that the construction of the generator is such that heat due to the hot gas generated within the generating-cham-
ber will not be transmitted to the liquid-res-
ervoir to any considerable extent. This is a
20 feature of importance, inasmuch as it is found in practice that the feed of liquid is much more uniform and the rate of generation of gas correspondingly more uniform when the liquid is kept cool. It will also be noted that
25 the construction of the reservoir is such that a relatively high head of pressure will be maintained above the liquid-outlet until the reservoir is practically empty. It is further to be noted that the insulating-space sur-
30 rounding the carbid-receptacle prevents the transmission of the intense heat present in the mass of carbid to the walls of the generator, so that the latter, although heated to a certain degree by the hot gas, nevertheless
35 may be readily handled. The making of the lower end of the carbid-cup convex and at-
taching it to the end of the generator at the central portion only is therefore a feature of importance, and not only this but this form
40 of the cup greatly facilitates the dislodgment of the residue, which has a tendency to cake during slaking.

While I have herein described what I deem to be a preferred embodiment of my invention, yet it will be obvious that certain details thereof may be modified to some extent without departing from the spirit of the invention and without involving more than ordinary mechanical skill. I do not, therefore,
45 wish to be limited to the precise details de-
scribed except as made the subject of specific claims.

I claim as my invention—

1. In an acetylene-gas generator, the combi-
55 nation with a carbid-receptacle made through-
out a portion of its height of uniform cross-
sectional area, of a follower arranged to fit within said portion and consisting of a plate of spring metal having a peripheral flange
60 turned at an angle to the plate and adapted to fit against the side walls of the carbid-re-
ceptacle, said flange being divided from its

margin inwardly to form one or more integral spring-tongues which frictionally and yieldably engage the sides of the carbid-re-
ceptacle and said follower being provided with a central opening surrounded by an up-
standing outwardly-flaring flange, which acts as a funnel to direct the liquid through the central opening thereof.

2. In a portable acetylene-gas generator, the combination with the generator-chamber having a removable lower end closure, of a cup-shaped carbid-receptacle of smaller cross-
sectional area than the interior of the gener-
ating-chamber, and having a convex bottom
70 rigidly attached at its central part only to the lower end closure, whereby said cup is removable with the latter and an insulating-space is formed extending between all parts 8c of the cup and outer walls of the generator except at the point of attachment between the cup and end closure, and a follower fit-
ting within said cup and having yielding frictional engagement with the sides thereof 85 whereby the carbid is confined in a compact body.

3. In an acetylene-gas generator the combi-
nation with a generating-chamber, a source 90 of liquid-supply and an inlet-port admitting liquid to the upper part of the generating-chamber, of a valve controlling said port, mechanism for adjustably holding said valve fixed open a definite degree, and a substan-
tially rigid liquid-directing guide projecting 95 freely downward through the space of the generating-chamber immediately below the inlet-port and forming a substantially con-
tinuous path for the liquid from said port through the space and into the carbid, where-
100 by the flow of liquid is made substantially uniform and is led by gravity to the carbid and is prevented from forming separate drops.

4. In an acetylene-gas generator, the combi-
nation with a generating-chamber, a source 105 of liquid-supply, a needle-valve port, a need-
le-valve controlling said port, and arranged to project at its lower end through and be-
yond the port, of a substantially inflexible li-
quid-directing guide mounted to extend from 110 a point in proximity to the projecting end of the needle-valve downwardly into the mass of carbid so as to form in effect an extension of the needle-valve point, whereby the liquid is caused to flow from the point of the needle 115 onto the guide in a relatively uniform stream.

In testimony that I claim the foregoing as my invention I affix my signature hereto, in the presence of two subscribing witnesses, this 22d day of February, A. D. 1898.

CHARLES L. ZIMMERMAN.
